(57) **CLAIM**

The ornamental design for an SSD heat sink as shown and described.

DESCRIPTION

FIG. 1 is a top, front right side perspective view of my new design for a SSD heat sink

FIG. 2 is a bottom, rear left-side perspective view thereof,

FIG. 3 is a right-side elevation view thereof,

FIG. 4 is a left-side elevation view thereof,

FIG. 5 is a front elevation view thereof,

FIG. 6 is a rear elevation view thereof,

FIG. 7 is a top plane view thereof,

FIG. 8 is a bottom plan view thereof; and,

FIG. 9 is a bottom, rear left-side perspective view thereof with a thermal adhesive strip for mounting on an SSD shown in dotted line, which forms no part of the claimed design.
